UNITED STATES PATENT OFFICE.

DIRK FRANS WILHELM, OF DOORWERTH, NEAR ARNHEM, NETHERLANDS, AS-SIGNOR TO VEREENIGDE NEDERLANDSCHE RUBBERFABRIEKEN, OF HEVEADORP, NETHERLANDS, A DUTCH COMPANY

VULCANIZING MOLD FOR RUBBER FOOTWEAR.

Application filed August 13, 1924. Serial No. 731,860.

To all whom it may concern:

Be it known that I, DIRK FRANS WILHELM, a subject of the Queen of the Netherlands, residing at Doorwerth, near Arnhem, Netherlands, have invented certain new and useful Improvements in Vulcanizing Molds for Rubber Footwear, of which the following is a specification.

This invention relates to certain novel and useful improvements in the manufacture of rubber footwear such as, for instance, sandals, blucher shoes, etc., and has particular application to improvements in the construction and arrangement of the vulcanizing mold parts.

In my previous process of manufacturing molded rubber footwear a four-part mold is employed, said mold being composed of two side molds, a sole-mold and a last or form for supporting the shoe to be molded. Where the side molds come together over the vamp there is then formed upon the shoe a seam, rib or fin of rubber which extends from the opening at the top of the shoe down across the instep and to the end of the toe where the upper joins the toe. This is to some extent disadvantageous as it mars the appearance of the shoe and also for the reason that where the side molds join on the center line they are liable to pinch or crimp the lining of the shoe in between the two parts, whereby the article is damaged.

In order to avoid the said disadvantage I have suggested to employ a five-part mold comprising a front member adapted to act as a mold for a portion of the instep, two side members for receiving that portion of the shoe between the front mold members and the heel, a sole-mold and a last or work-support, but such a five-part mold, while avoiding a seam over the vamp, has the inconvenience that it is still more difficult to make with the required accuracy in view of the high pressure which it has to stand during the vulcanization.

To overcome the objections above recited I form my mold as hereinafter described with reference to the annexed more or less diagrammatic drawing, in which Fig. 1 is a vertical longitudinal sectional view taken through my novel three-part mold, Fig. 2 is a cross-sectional view taken along the line II—II in Fig. 1, Fig. 3 is a cross-sectional view taken along the line III—III in Fig. 1

and Fig. 4 is a vertical longitudinal sectional view of an auxiliary last.

Referring now to the drawing in detail, 5 designates a last post or stem carrying the last or shoe-support 6, the preferred position of which being as shown with the sole portion uppermost. The lower end 5^a of the post or stem 5 is tapered so as to make a snug fit in a correspondingly shaped seat 7^a of the upper-mold 7, which is provided with a matrice adapted to receive not only the front portion or vamp of the shoe, but also the sides and the back thereof up to the plane 8 where the upper joins the sole. The third section of the mold is the top or sole-mold 9, the matrice of which has a contour adapted to mold the balance, i. e. the sole 11 and the heel 12 on the shoe.

It will be readily understood that it is necessary for the molds 7 and 9 to be so formed that the walls of their matrices, starting from the plane of junction 8, are more or less inwardly inclined, as any outward slope of these walls would interfere with the proper removal of said molds after the vulcanization and tend to damage the article. This inward slope of the walls all around the matrices is a characteristic feature of my novel mold and one which, as far as I am aware, is not met in any other mold for rubber shoes. Figs. 1, 2 and 3 of the drawing are illustrative of this special form of the molds, but obviously any cross or longitudinal section over the mold would bring out the said novel feature.

The upper face of mold 7 and the lower face of mold 9 are formed with rims or bosses *a* and *b* surrounding the edges of the mold cavities and meeting in sharp edges on the interior of the mold. These shear edges serve to trim off the surplus material that is forced or squeezed out of the mold, thus making a smooth finish around the edge of the sole. A similar rim or boss *c* surrounds the lower edge of the cavity in mold 7 for trimming off the surplus material that is forced into the channel or vent 13 extending around the stem 5 contiguous with the portion of the last 6 which forms the rim around the opening of the shoe.

The upper-mold 7 is provided with dowel pins 14 fitted to corresponding sockets 15 in the sole-mold 9.

The means for operating the molds 7 and

9 to force them up against the shoe made up on the last or work support 6 have not been shown as they do not form part of my present invention, but I wish it to be understood 5 that the required pressure may be brought about by any conventional or convenient instrumentalities for this purpose. Neither does the drawing illustrate the means for simultaneously raising the temperature of 10 the shoe as any one skilled in the art will know how to bring about the required heat.

After the vulcanization or cure the mold sections 7 and 9 are moved away from each other and the shoe taken off the last 6. In 15 view of the fact that the contours of the last 6 correspond with those of the matrices in the molds it goes without saying that during this removal of the last the shoe must be put under tensional stress, so that it is essential 20 for the lining of the shoe to be sufficiently elastic. In practice I have found that with a lining of knitted web or texture very satisfactory results are obtained, but instead of knitted fabric, canvas, duck or other woven 25 material may be used, provided the threads thereof run more or less diagonally.

The shoe thus obtained is not yet suitable for footwear as its walls do not bulge or jut out. This, however, can be remedied in a 30 very simple manner by putting the shoe on a last of the required form, for instance, as shown in Fig. 4, and then subjecting it to an after-cure without pressure, whereby the shoe assumes and retains the desired contours and its final shape.

Fig. 1 shows a metallic stiffening shank 14 embedded in the sole portion between the heel 12 and the ball portion. Such a metallic shank is of essential importance in 40 shoes provided with heels for supporting the

arch of the foot, but I wish it to be understood that my present invention is not limited to the use of such a shank.

Finally I wish to remark that my present invention may be applied to molds for shoes 45 of any description and character as the principal feature of the invention is to avoid the necessity of using more than two mold sections in addition to the last or form.

Having thus described my invention, what 50 I claim as new, and desire to secure by Letters Patent, is:—

1. A method of manufacturing rubber 55 footwear which consists in first vulcanizing the article under pressure in a mold comprising an upper-mold, a sole-mold and a last for supporting the article, and thereafter subjecting the article to an after-cure on another last.

2. A method of manufacturing rubber 60 footwear which consists in first vulcanizing the article under pressure in a mold comprising an upper-mold, a sole-mold and a last for supporting the article, the matrices 65 of the mold sections being so formed that their walls, starting from the plane of junction of said sections, slope more or less inwardly, and thereafter subjecting the article to an after-cure on a last presenting the desired final form.

3. A method of manufacturing rubber 70 footwear which consists of first vulcanizing the article under pressure in a mold comprising a section to receive the entire upper, a sole section and a last for supporting the 75 article, and thereafter subjecting the article to an after-cure on another last.

In testimony whereof I affix my signature.

DIRK FRANS WILHELM.
